US00D939452S

(12) **United States Design Patent** (10) **Patent No.:** **US D939,452 S**
Yang et al. (45) **Date of Patent:** **** Dec. 28, 2021**

(54) **REMOTE CONTROL FOR MASSAGE APPARATUS**

(71) Applicant: **ETEKCITY CORPORATION**, Anaheim, CA (US)

(72) Inventors: **Lin Yang**, Shenzhen (CN); **Hai Yang**, Shenzhen (CN)

(**) Term: **15 Years**

(21) Appl. No.: **29/708,002**

(22) Filed: **Oct. 2, 2019**

(30) **Foreign Application Priority Data**

Apr. 3, 2019 (CN) 201930146931.6

(51) LOC (13) Cl. **14-03**

(52) U.S. Cl.

USPC **D13/168**; D24/200

(58) **Field of Classification Search**

USPC ..... D13/168; D14/218, 138 AA; D24/200, D24/214, 215

(57) **CLAIM**

The ornamental design for a remote control for massage apparatus, as shown and described.

DESCRIPTION

FIG. 1 is a perspective view of a remote control for massage apparatus showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is another perspective view thereof.

1 Claim, 8 Drawing Sheets
